UNITED STATES PATENT OFFICE.

DANIEL H. BUCKWALTER, OF CHIPPEWA FALLS, WISCONSIN, ASSIGNOR TO HIMSELF AND FREDRICK LANGE, OF SAME PLACE.

IMPROVEMENT IN MIDDLENS-PURIFIERS.

Specification forming part of Letters Patent No. 158,025, dated December 22, 1874; application filed August 15, 1874.

To all whom it may concern:

Be it known that I, DANIEL H. BUCKWALTER, of Chippewa Falls, in the county of Chippewa and State of Wisconsin, have invented an Improved Machine for Separating and Purifying Wheat-Middleings, of which the following is a specification:

In the manufacture of wheat flour it has been found by experiment that there is a percentage of fine flour that is lighter than the fine fuzz of the wheat which is liberated by grinding, but which is also heavier than the dust of the middleings.

The object of my invention is to combine in one machine certain devices which will separate the coarse from the fine middleings, eliminating, at the same time, the impurities from them; second, to separate the fine flour from the fine middleings; and third, to separate the dust from the fine flour; and, it consists, first, in the peculiar construction and manner of operating the bolting-reel, which has a longitudinal vibration, as well as an intermittent rotation; also, in the peculiar construction and arrangement of the separating devices, as more fully hereinafter set forth.

Figure 1, Sheet 1, is a perspective view. Fig. 2, Sheet 2, is a side elevation. Fig. 3 is a front elevation. Fig. 4 is a rear elevation. Fig. 5, Sheet 3, is a longitudinal vertical section on x x , Fig. 4. Fig. 6 is a cross-section at y y in Fig. 5. Fig. 7 is a similar section at z z . Fig. 8 is a detail section of the reel-gear. Fig. 9 is a similar detail of the reel-shaft and central perforated tube. Fig. 10 is a plan of the same.

In the drawing, A represents the frame of the machine, surmounted by a hopper, B, through the throat of which a roller, C, is transversely journaled in bearings on top of the frame, and which, by its rotation, causes the middlelings to feed into a spout, D, below, which is enlarged and inclined to spread the middlelings before discharging them. The bottom of the spout D is fitted with a coarse bolting-cloth, which effects the first separation, or rather prepares the middlelings for the first separation. E is the reel-shaft, which is triangular in cross-section. The tail end rotates

and slides in a socket in a vertically-adjustable bridge-tree, a, to adjust it to such inclination as the middlelings may require. The upper end is sleeved through a triangular opening in the hub or bushing of a pinion, F, journaled in a mortise in a bridge-tree, a', in the head part of the frame. The reel-shaft is provided with arms b, Fig. 7, which carry the ribs c, covered with bolting-cloth E², which thus forms a triangular reel. A slotted sleeve, E¹, is concentrically sleeved on the shaft inside the bolting-reel. The head end of the shaft is round in cross-section, and is suspended in an eye at the lower end of a three-inch plate-spring, d, pendent from the top of the frame, which spring pulls the reel-shaft toward the head of the machine. A rod, e, is also secured to this spring and the shaking-spout D. G is the driving-shaft, journaled across the front or head end of the frame, carrying an eccentric, f, which is embraced by an open box, g, suspended by two plate-springs, h, from the frame. In the rear plate of this box the end of the reel-shaft is journaled, but bearing at its extremity upon the eccentric. My object in journaling the shaft in the suspended bearing is to take the friction off the hub of the pinion F. H is a suction-fan, driven by a belt from a pulley on one end of the driving-shaft. This fan and its case are located on top of the frame-work, which is cased in on the top. I is the suction-tube, communicating at one end with the fan, and then turned down over the tail end of the frame, turned in, and terminating in the lower end of the reel, above the shaft. J is a counter-shaft, journaled in the lower front part of the frame, and is driven by a belt from the driving-shaft. On its inner end is a bevel-pinion, K, meshing with a bevel-gear, K', on the front end of a conveyer-shaft, L, longitudinally journaled in the lower part of the frame, with a screw-conveyer, M, mounted upon it, and rotating within a trough, N, which may be provided with one or more valves, to discharge a portion of the material, for returning them either for regrinding or for repurification, the rest being discharged at the tail end. O is a spur-gear on the conveyer-shaft, meshing with and giving

motion to a large pinion, P, on a counter-shaft, j, above it, on which is also mounted a wheel, Q, having four teeth, i, on its periphery in one group, all the rest being cut off. These teeth i, in each revolution of the counter-shaft, engage with the pinion F, sleeved on the reel-shaft, and rotate it one-third of a revolution, causing the reel-shaft to rotate from one flat side to the next, upon which its tail end drops in its bearing with such impact as that the concussion will free the cloth from the adhering middlings, and thus obviate the necessity of brushing it for that purpose. Over the reel is suspended an arched casing, R, above which is a large opening, k, in the top casing, leading into the fan-case, and which opening is provided with one or more valves to regulate the upward current. Extending below the reel, nearly to the trough, N, are the sides R', suspended from the top casing of the machine. S is a blast-spout, attached to the mouth of the fan-case, and is curved upward, and extends along over the top of the machine, with a hopper, S¹, over the hopper B, and another one, S², at the extremity beyond the machine, both these hoppers being provided with valves s s' in their bottoms. In practice, the total length of the blast-spout is about twenty feet. The hopper S² is covered at the top with a bolting-cloth, l, of very fine mesh, which is kept free by two cloth wipers, m, on a shaft, T, revolving in standards n at the sides, the said shaft T being driven by a belt from any convenient pulley on the machine. The fan is driven by a belt from the driving-pulley.

The first separation occurs when the middlings enter the reel by the suction of the fan, which draws into the suction-spout the finer and lighter portions which are blown up into the blast-spout s, reaching it through the spout or tube I. The heavier particles pass into the reel, which separates the coarse impurities, which are discharged at the tail end over an apron, U. What passes through the bolt is carried away by the conveyer, except the very fine particles of light flour, which, as

they are floating or falling slowly down, are met by influent currents of air entering between the conveyer-trough and the sides R', carried up by the suction over the arched casing R into the fan, and discharged into the blast-trunk. The heavier particles settle in the hopper S¹, where the second separation occurs, while the lighter particles (fine flour) pass along to the end, where the fine cloth in the end hopper S² permits the dust to escape, while it retains the flour, which, thus separated, can be drawn off, from time to time, through the bottom valve s', the third separation occurring in the hopper S².

The gearing is so proportioned as to give the reel four hundred vibrations per minute, and one revolution on its axis per minute, or three concussions per minute, which will keep the meshes of the bolt free from adhering particles.

The tail end of the machine is closed up, except an opening at the discharge-apron U, in order that the current of air to supply the spout I may be drawn from the head end of the reel.

What I claim as my invention, and desire to secure by Letters Patent, is—

1. The triangular reel-shaft E, bolting-reel E², and pinion F, in combination with eccentric f and gearing, for continuously reciprocating and intermittently rotating the bolting-reel and reel-shaft, substantially as described.

2. The combination of the suction-fan H, suction-spout I, blast-spout S, provided with the hoppers S¹ S², the valves s s', shaft T, wipers m, and cloth l, with the bolting-reel E², shield R, sides R', and frame A, substantially as and for the purpose set forth.

3. The partially-toothed gear Q and pinion F, arranged as described, for intermittently rotating the angular reel-shaft E, having a longitudinal movement in said pinion, for the purpose set forth.

DANIEL H. BUCKWALTER.
